UNITED STATES PATENT OFFICE

148,324

DESIGN FOR A RADIO CABINET

Joseph D. Portanova, Los Angeles, Calif., assignor
to Hoffman Radio Corporation, Los Angeles,
Calif., a corporation of California

Application September 9, 1946, Serial No. 133,186

Term of patent 3½ years

(Cl. D56—4)

To all whom it may concern:

Be it known that I, Joseph D. Portanova, a citizen of the United States, residing at West Los Angeles, California, have invented a new, original, and ornamental Design for a Radio Cabinet, of which the following is a specification, reference being had to the accompanying drawing, forming a part thereof, in which:

Fig. 1 is a front perspective view of a radio cabinet embodying my new design.

Fig. 2 is a rear elevational view thereof, and
Fig. 3 is an end elevational view thereof.

The characteristic features of the design are shown in solid lines in the drawing.

I claim:

The ornamental design for a radio cabinet, substantially as shown and described.

JOSEPH D. PORTANOVA.
